UNITED STATES PATENT OFFICE.

WILLIAM M. SCOTT, OF RADNOR, PENNSYLVANIA.

ELECTROMAGNETIC SWITCH.

1,097,680.

Specification of Letters Patent. Patented May 26, 1914.

Original application filed March 8, 1912, Serial No. 682,506. Divided and this application filed April 5, 1913. Serial No. 759,086.

To all whom it may concern:

Be it known that I, WILLIAM M. SCOTT, a citizen of the United States, residing in Radnor, State of Pennsylvania, have invented certain new and useful Improvements in Electromagnetic Switches, of which the following is a specification.

My invention relates to electric switch or circuit breaker construction.

10 My invention resides in a switch or circuit breaker comprising electro-responsive means and means for mechanically holding a contact member in normal position, the electro-responsive means releasing the same 15 from mechanical control and itself restraining the contact member.

My invention resides in further features hereinafter described.

20 This application is a division from my application Serial No. 682,506, filed March 8, 1912, upon which issued Letters Patent No. 1,058,200.

For an illustration of one of the forms my invention may take reference is to be 25 had to the accompanying drawing, in which:

Figure 1 is a side elevational view, partly in section, of switch mechanism embodying my invention. Fig. 2 is a front elevational view of the same. Fig. 3 is a side view of 30 one of the members. Fig. 4 is a side view of a coöperating member. Fig. 5 is an elemental and diagrammatic view illustrating the switch mechanism and a mode of electrically connecting the same.

35 Referring to the drawing, the switch or circuit breaker comprises a base 54 of insulating material upon which is secured an electro-magnet having the core 55, winding 56 and jacket 57. Disposed in front of the 40 electro-magnet is the armature 58 having lost motion pivotal connection at 59 with the arm 60 pivoted at 61 to the bracket 62 upon the jacket or housing 57. At 63 the latch 64 is pivoted to the arm 60. On the jacket 57 45 is formed a notch 65 which is engaged by the hook latch 64 to hold the arm 60 in the position shown in Fig. 1 as hereafter described. The latch 64 has a lug 65^a adapted to be engaged by the lug 66 on the armature 58. There may be provided on the 50 latch 64 a weight 67 causing the latch 64 to engage the notch 65 even in the case where the base 54 is horizontal. At its upper end the arm 60 carries a contact roller

68 adapted to engage with the contact spring 55 69 mounted upon the base 54.

Pivoted at 61 on the bracket 62, but independently of the arm 60, is the actuator or operating lever 70 carrying a movable contact 71, electrically connecting through lever 60 or arm 60 with the roller 68. This movable contact 71 is adapted to engage with the stationary contact 72 secured upon the base 54. On the arm 70 is provided a surface 73 adapted to engage the lug 74 on the lower end of the arm 60 for limiting counter-clockwise rotation of arm 70, as viewed in Fig. 1. Wrapped around the pivot 61 is a spring 75 whose one end engages the arm 60 and whose other end engages the bracket 70 62, the tension of the spring being such that it tends to rotate the arm 60 in a clockwise direction on its pivot 61 as viewed in Fig. 1. Between the brackets 62 is a surface 73^a provided for engaging projection 74^a on arm 75 60 thus limiting outward or clockwise movement of arm 60 which movement is retarded by the spring buffers 75^a.

In Fig. 5 the stationary contact 69 is shown connected with conductor 81, such 80 conductor 81 being in electrical connection through contact 69, members 60 and 70, contact 72, conductor 80, magnet winding 56 and conductor 79 with conductor 78, the conductors 78 and 81 forming part of any 85 desired circuit.

An indicating device, such as incandescent lamp L, has its terminals connected to conductors 78 and 81, that is, the lamp L is connected in shunt with the switch mechanism and its magnet winding so that, when the switch is closed as shown in Fig. 5, the lamp L is in effect short circuited and does not glow, thereby indicating that the switch mechanism is closed. When the switch 95 mechanism opens, the lamp L glows, indicating the condition of the switch mechanism.

The operation is as follows: With the parts in circuit closing position as indicated in the drawing, if the circuit including conductors 78 and 81 is conducting current, the electro-magnet is energized and attracts its armature 58 thus holding the contact member 60 in circuit closing position, but raising the latch 64 by engagement of lug 66 100 with projection 65^a on the latch 64; that is to say the electro-magnet upon its energization has transferred the restraint of the member 105

60 from latch 64 to the electro-magnet itself. If now, as upon no load, low voltage, or other similar electrical condition in the circuit, the current through the magnet winding 56 becomes zero or falls to sufficiently low value, the electro-magnet can no longer exert upon armature 58 sufficient attractive force to hold the member 60 in closed position, and consequently the spring 75 will 10 throw member 60 outwardly in clock-wise direction about its pivot 61, as viewed in Fig. 1, thereby rupturing the circuit, it being understood that the lamp L has so high a resistance that the circuit mentioned is in effect broken; or if the lamp L be omitted said circuit is completely broken. To again close the switch mechanism, the operator moves the actuator 70 in a counter-clock-wise direction about pivot 61, thereby breaking 15 contact between contact members 71 and 72, and as the movement of the member 70 is continued the member 60 is rotated to the position shown in Fig. 1, whereupon the latch 64 moves into locking position and 20 restrains the member 60 in the position shown. The circuit through the winding 56 of the electro-magnet is however, at this stage, incomplete because contact members 71 and 72 are not in engagement with each 25 other. The operator now depresses the lever 70 in clockwise direction about pivot 61 to the position shown in Figs. 1 and 5, where contacts 71 and 72 are in engagement with each other. If now there is current in 30 the circuit the electro-magnet will be energized and will transfer the restraint of member 60 from latch 64 to itself, as above described. If at the end of the closing movement above described there is no current in 35 the circuit, restraint of member 60 is by latch 64, until current is present in the circuit and to a degree sufficient to attract armature 58 for the purposes above described.

40 From the foregoing description it is apparent that the switching mechanism may be closed and locked closed whether or not there be current in the circuit to energize the electro-magnet; and that when there is such current present the restraint of the 45 contact member is transferred from the latch to the electro-magnet.

What I claim is:

1. In an electric switch, a movable contact member, means for restraining said contact member in normal position, and an electro-magnet having an armature connected with said contact member, said armature when attracted freeing said contact member from 55 said restraining means and itself restraining said contact member.
2. In an electric switch, a movable contact member, a latch for restraining the same in normal position, and an electro-magnet having an armature connected with said contact member, means for restraining 60

tact member for actuating said latch and itself restraining said contact member.

3. In an electric switch, a movable contact member, means for restraining the same in normal position, an actuator for moving 70 said contact member to normal position, a switch controlled by said actuator, and an electro-magnet controlled by said switch and having an armature connected with said contact member, said armature when attracted 75 transferring the restraint of said movable contact member from said restraining means to itself.

4. In an electric switch, a movable contact member, means for restraining the same in 80 normal position, an actuator for moving said contact member to normal position, a switch controlled by said actuator, and an electro-magnet controlled by said switch and having an armature connected with said contact 85 member, said armature when attracted holding said restraining means in inoperative position and itself restraining said contact member.

5. In an electric switch, a movable contact 90 member, means for restraining the same in normal position, an actuator for moving said contact member to normal position, a switch controlled by said actuator, and an electro-magnet having an armature connected with 95 said contact member, said armature when attracted transferring restraint of said contact member from said restraining means to itself, said switch and said contact member included in the same circuit. 100

6. In an electric switch, a movable contact member, means for restraining the same in normal position, an actuator for moving said contact member to normal position, a switch controlled by said actuator, and an electro-magnet controlled by said switch and having an armature connected with said contact member, said armature when attracted 105 transferring restraint of said contact member from said restraining means to itself, said switch and said contact member included in the same circuit. 110

7. In an electric switch, the combination with a movable contact member, of means for restraining the same in normal position, an actuator for moving the same to normal position, a switch opened by said actuator when said actuator moves said contact member to normal position and closed upon reversed movement of said actuator, and an electro-magnet controlled by said switch and having an armature connected with said contact member, said armature when attracted 115 transferring restraint of said contact member from said restraining means to itself. 120

8. In an electric switch, the combination with a movable contact member, of means for restraining the same in normal position, an actuator for moving the same to normal position, a switch opened by said actuator 125

- when said actuator moves said contact member to normal position and closed upon reversed movement of said actuator, and an electro-magnet controlled by said contact member and having an armature connected therewith, said armature when attracted transferring restraint of said contact member from said restraining means to itself. 5
9. In an electric switch, the combination with a movable contact member, of means for restraining the same in normal position, an actuator for moving the same to normal position, a switch opened by said actuator when said actuator moves said contact member to normal position and closed upon reversed movement of said actuator, and an electro-magnet controlled by said switch and said contact member and having an armature connected with said contact member, 15 said armature when attracted transferring restraint of said contact member from said restraining means to itself.
10. In an electric switch, the combination with a movable contact member, of means for restraining the same in normal position, an actuator for moving the same to normal position, a switch opened by said actuator when said actuator moves said contact member to normal position and closed upon reversed movement of said actuator, and an electro-magnet connected in series with said switch and said contact member and having an armature connected with said contact member, said armature when attracted transferring restraint of said contact member from said restraining means to itself. 25
11. In an electric switch, the combination with a movable contact member, of a latch carried thereby for restraining the same in normal position, and an electro-magnet having an armature carried by said contact member for actuating said latch and itself holding said contact member in normal position. 40
- 45 12. In an electric switch, the combination with a movable contact member, of a latch for restraining the same in normal position, and an electro-magnet having an armature connected with said contact member through a lost motion connection, said armature adapted to actuate said latch and itself hold said contact member in normal position. 50
13. In an electric switch, the combination with a movable contact member, of a latch carried thereby for restraining the same in normal position, and an electro-magnet having an armature connected with said contact member through a lost motion connection, said armature adapted to actuate said latch and itself hold said contact member in normal position. 55
14. In an electric switch, the combination with a movable contact member, of a latch for restraining the same in normal position, and an underload electro-magnet having an armature connected with said contact member for actuating said latch to transfer the restraint of said contact member from said latch to said armature. 60
15. In an electric switch, the combination with a movable contact member, of a latch for restraining the same in normal position, an underload electro-magnet having an armature connected with said contact member, an actuator movable independently of said contact member for moving the same to normal position, a switch opened when said actuator moves said contact member to normal position and closed upon reverse movement of said actuator to close the circuit of said electro-magnet, said armature when attracted transferring the restraint of said movable contact member from said latch to itself. 70
- In testimony whereof I have hereunto affixed my signature in the presence of the two subscribing witnesses. 75
